WILLIAM F. DIESEL AND EUGENE R. WEBER, OF ROCHESTER, NEW YORK, ASSIGNEES
TO SARGENT & GREENLEAF, INC., OF ROCHESTER, NEW YORK, A CORPORATION OF
NEW YORK.

ADJUSTABLE LOCK.

Application filed January 9, 1922. Serial No. 528,069.

To all whom it may concern:

Be it known that we, WILLIAM F. DIESEL and EUGENE R. WEBER, of Rochester, in the county of Monroe and State of New York, have invented certain new and useful Improvements in Adjustable Locks; and we do hereby declare the following to be a full, clear, and exact description of the same, reference being had to the accompanying drawings, forming a part of this specification, and to the reference numerals marked thereon.

This invention relates to locks and more particularly to the variety which are adjustable for the operation by different selected keys, the chief object of the invention being to provide a simple, reliable and efficient lock of this character affording a high degree of protection against unauthorized operation, while of a simple form of construction comprising comparatively few parts and inexpensive to manufacture. To these and other ends the invention resides in certain improvements and combinations of parts all as will hereinafter be more fully described, the novel features being pointed out in the claims at the end of the specification.

In the drawings:

Figure 1 is a front elevation of a lock embodying the present invention;

Figure 2 is a rear elevation of the same;

Figure 3 is an enlarged front elevation of the lock with its cover plate removed to show the working parts in normal locked position;

Figure 4 is a view similar to Figure 3 but showing the parts under operation by a primary key;

Figure 5 is a view similar to Figure 4 with some of the tumblers removed and showing the position of the parts at the completion of the operation of the primary key;

Figure 6 is a view similar to Figure 5 but showing the parts moved to unlocked position by a secondary or operating key;

Figure 7 is a similar view partly broken away showing a guard tumbler in position for cooperation with an adjusting or change key;

Figure 8 illustrates the adjustment of the tumblers to a selected secondary key;

Figure 9 is a view similar to Figure 8 with parts removed to show the operation of

the guard tumbler during adjustment of the lock;

Figure 10 is a section on the line 10^a—10^a of Figure 3;

Figure 11 is a section on the line 11^a—11^a of Figure 4;

Figure 12 is a section on the line 12^a—12^a of Figure 6;

Figure 13 is a view similar to Figure 12 but showing the adjusting key in the lock;

Figure 14 is a section on the line 14^a—14^a of Figure 7;

Figure 15 is a section on the line 15^a—15^a of Figure 9;

Figures 16 and 17 are sectional views substantially on the line 16^a—16^a of Figure 8 showing the operation of the adjusting key;

Figure 18 is an enlarged detail view of the interengaging parts of the adjustable tumbler sections.

Similar reference numerals throughout the several views indicate the same parts.

The invention is embodied in the present instance in a lock of the multiple key type operated in succession by primary and secondary keys. The tumbler means operated by the secondary keys comprises tumblers adjustable to render them responsive to different selected operating keys, and also guard tumbler means responsive to any one of the series of secondary keys. The adjustable tumblers are adjusted by a change key inserted through openings therein, and in the guard tumbler, and also through an opening in the bolt in the extended position of the latter, so that all of these parts are maintained in position during the adjustment of the tumblers for co-operation with a different operating key. The guard tumbler is also arranged to prevent withdrawal of the change key during adjustment of the lock, these various features providing advantages explained more fully hereinafter and being embodied in a simple form of construction requiring but a single set of tumblers. The complexity usual in locks of this type is thus avoided and a construction provided which is more durable and reliable and inexpensive to manufacture because of its simplicity.

Referring to the drawings for a more detailed description, the present embodiment comprises a lock having a casing indicated generally at 20, adapted to be secured to

the inner side of a door or other closure by fastening means passing through openings 21 at the corners of the casing. At 22, on the front of the lock, is a cover plate secured thereon as by means of a screw 23, and having a sleeve 24 in which and in the rear side of the casing the plug or barrel is rotatably supported. The latter sleeve and barrel are extended to project through an opening in a door adjacent the front thereof for purposes of accessibility. The rear wall of the casing is provided with an opening 25 for the reception of an adjusting or change key.

15 The bolt is shown at 26, Figure 9, as sliding in an opening in an end of the casing and extending at one side lengthwise of the same adjacent its opposite end where it is slotted as at 27 for supporting, sliding engagement with a spindle 28 fixed on the casing. The outward or locking movement of the bolt is limited by engagement of a shoulder 29 thereon with a post 30 on the casing which also serves to limit movements 20 of the tumbler means as hereafter explained. The bolt at its lower edge is recessed as at 31 to receive an arm 32 of the usual or any suitable construction fixed on the barrel 33 which is rotated as usual by the keys for 25 sliding the bolt. The latter carries also a stub or fence 34 and has formed therein an opening 35, Figure 6, arranged to register with the change key opening 25 in the casing when the bolt is in extended or locked 30 position.

Each of the single set of tumblers employed is preferably pivotally supported on the spindle 28 and moved to bolt releasing position by keys inserted in a common keyhole in the barrel 33. As stated, the present embodiment is of the multiple key type operated by primary and secondary keys and to this end the set of tumblers comprises a primary or sliding tumbler 36 best illustrated in Figures 3 to 6 inclusive. This tumbler is in the form of a plate having an elongated opening 37 at one end supporting it for pivotal and sliding movement on spindle 28. The other end of the tumbler is 40 gated as at 38, to receive the fence on the bolt, one side of the gate having an offset shoulder 39 and the other having an offset shoulder 40 connected by an inclined surface 41 with the side of the gate proper. A 45 spring 42 carried by the tumbler and encircling spindle 28 for engagement with the top of the casing, tends to move the tumbler downwardly until stopped by post 30. The lower side of the tumbler is formed with a 50 projecting shoulder 43 adjacent the barrel for cooperation with the preparatory key. In locked position of the parts the primary tumbler occupies the position shown in Figure 3. The primary or preparatory key 43^a

of the present lock is illustrated in Figure 65 11 as stepped to clear all other tumblers except the primary one. When the primary key is inserted in the barrel and turned in a clockwise direction to the position shown in Figure 4, the primary tumbler is raised 70 and during the return rotation and withdrawal of the key the tumbler is lowered and moved by engagement of the key with shoulder 43 toward the fence as shown in Figure 5, so that the offset shoulder 40 of its gate 75 comes to rest on the top of the fence. The tumbler remains in this position until the bolt is retracted by a secondary or operating key when the fence, sliding over the inclined gate surface 41, aligns the tumbler 80 and moves the same to the right to the position shown in Figure 6. When the bolt is again extended the primary tumbler drops to the initial position of Figure 3, requiring the operation of the primary key as described 85 for again unlocking the bolt.

The guard tumbler 44, best shown in Figures 7 and 9, is in the form of a plate and has a simple pivotal movement on spindle 28, being urged toward the key barrel by 90 means of a spring 45. This tumbler has at its bottom edge a sweep surface 46 which is engaged by a corresponding bit on all of the series of secondary keys, to raise and position the tumbler so that a gate 47 therein 95 is aligned with the fence to release the bolt. This tumbler has formed therein an opening or keyhole 48 arranged to register, when the tumbler is thus brought to bolt releasing position, with the keyhole 25 in the casing 100 through which the change key indicated at 48^a is inserted. The latter may thus be passed through the guard tumbler for maintaining the latter in raised though not in bolt releasing position, during adjustment of 105 the lock, and the adjusting or change key is recessed as at 49, Figure 17, in position to receive the top of the keyhole of the guard tumbler when the change key is fully inserted in the lock. After the guard tumbler 110 has been raised to bolt releasing position as shown in Figure 9, by one secondary key, and the change key inserted as described, the removal of this secondary key allows the guard tumbler to drop until the upper end 115 of its keyhole engages in the recess 49 of the change key, thus obstructing withdrawal of the latter until a secondary operating key is inserted and turned to raise the guard tumbler and release the change key. 120

It is evident from this construction, as shown in the drawings, that the guard tumbler normally obstructs the insertion of an object or change key through the opening in the casing for the latter and that one of the series of secondary keys corresponding to the lock must be employed to move the guard tumbler to position to release the bolt 125

and to permit the insertion of the change key. The latter, when inserted, is held against withdrawal by the guard tumbler which can only be moved to release the 5 change key and the tumbler and bolt by means of one of the secondary keys. This prevents improper adjustment of the adjustable tumblers hereafter described for the purpose of rendering them ineffective or 10 responsive to an instrument other than the secondary keys of the lock.

The adjustable tumblers, of which, in the present instance, there are four (4) indicated generally at 50, Figures 4 and 5, each 15 comprises two sections, a key actuated sweep section 51 and a gated detent section 52. These sections of each tumbler have abutting portions provided with interengaging parts or teeth 53, shown in detail in Figure 18, for connecting the same in different 20 positions of relative adjustment. Both sections are pivotally supported for movement together as one on spindle 28 and in addition the bearing opening for the spindle 25 in one section, preferably the detent section, is elongated to provide for movement of the sections relative to each other transversely of the spindle, or in other words, in a direction for engaging and disengaging 30 the cooperating teeth 53. The sections are shown disengaged in Figure 8 by such movement of the detent section toward the left, freeing the sweep section so that it may drop into positioning cooperation with a secondary 35 key to which the lock is to be made responsive, after which the sections are again connected together for movement as one. Preferably the detent sections are provided with spring elements 54 engaged with the 40 casing or other suitable part, for urging the detent sections yieldably toward the sweep sections to maintain them in connected relation. The sweep sections also are provided with spring elements 55 for 45 urging the same and the detent sections and connected therewith downwardly for cooperation with an operating key. As shown in Figure 18, the interengaging teeth 53 of the sections are bevelled to insure proper 50 engagement and are likewise provided with flat lateral faces serving to prevent any tendency of the teeth to move out of engagement under applied pressure.

The section of each adjustable tumbler 5 having the sliding movement described, preferably the detent section, is provided with a change key opening or keyhole 56 arranged to register with the openings or keyholes of the other adjustable tumblers, of 50 the guard tumbler and of the casing when the tumblers are moved to bolt releasing position. In this position of the parts the adjusting or change key may be inserted in the lock through each of the keyholes described including that of the bolt when ex-

tended. The change key is preferably provided with a bit 57 for engagement with the sides of the keyhole of the adjustable tumblers. The latter in the present instance are enlarged as shown so that they can be 70 engaged by the key to move the detent sections only when the key is properly inserted and rotated, and such movement of the key serves to actuate the detent sections out of engagement with the sweep sections to allow the latter to drop on the corresponding bits of the inserted secondary key. It is to be noted that when a secondary key has been employed to set up the tumblers, with the bolt extended, to permit the insertion of a change key, and the latter has been inserted in the lock as described and rotated, the change key holds the bolt extended and the tumblers in bolt releasing position or, in other words, with 85 their gates aligned with the fence, and the change key itself is maintained in the lock by the guard tumbler. Thus the tumblers cannot be arranged by the change key in an effective position, nor can they be adjusted 90 or set up to any object or key other than a secondary key of the lock series for the reason that one of the latter is required to raise the guard tumbler and thus release the change key and thereby release the bolt 95 and tumblers for subsequent operation. It is apparent also that the change key is so constructed that it cannot be withdrawn until it has been turned so as to release the adjustable tumbler sections for reengagement 100 with each other, and, of course, changing of the tumblers in the manner described can only be completed when the secondary key has been inserted and partially rotated to the proper position because of the shape of 105 the guard tumbler. Preferably the fence and the adjacent surfaces of the guard and adjustable tumblers are serrated as shown to insure against improper operation of the lock, as well understood in the art.

The operation of the lock has been explained in connection with the description of its construction and may be summarized as follows: In ordinary use the primary key is inserted in the lock and operated to 115 align and support the primary tumbler 26 on the bolt fence as shown in Figures 4, 5 and 11. Thereafter, the secondary operating key for which the lock is adjusted is inserted and rotated to line up the guard and adjustable tumblers and retract the bolt, Figure 6. When the latter is again extended to locked position, the tumblers fall out of alignment, requiring the use of both primary and secondary keys for repetition of 120 the unlocking operation, as described. When it is desired to adjust the lock to render it responsive to a different secondary key, the closure controlled by the lock must be opened to afford access to its rear side for insertion 125 130

therein of the change key. Before the latter is inserted, however, the bolt must be extended to locked position to bring its key-hole to position to permit insertion of the change key. The operation of the change key exclusively at the rear side of the lock or on the inner side of the closure, renders the lock of course more secure against unauthorized operation and the necessary extension of the bolt prevents the closure from being shut and accidentally producing a "lock-out."

The lock may then be adjusted by first inserting and partially rotating the previous or old secondary key, indicated at 58, the primary key not being used during adjustment because not required and for the further reason that its use would set up the primary tumbler in such position as to prevent insertion of the change key, as is apparent from Figure 5. The primary slide therefore blocks the withdrawal of the bolt, as shown in Figure 8, and thus limits the movement of the secondary key to the partial rotation referred to above and to the position in which the guard and adjustable tumblers are brought to bolt releasing position in which their openings for the change key are aligned. The change key is then inserted and rotated as described to disconnect the sections of each adjustable tumbler, as shown in Figure 8, and allow the sweep sections to drop against the stop post 30. The previous secondary key is then removed, Figure 7, and the guard tumbler drops slightly and obstructs removal of the change key during the adjustment. The new secondary key, indicated at 59, Figures 8 and 9, is then inserted and partially rotated to raise the guard tumbler and thus permit the withdrawal of the change key. The bits of the new key thus adjust the sweep sections to position to render the lock responsive to it alone and the withdrawal of the change key forces the detent sections to reengage the sweep sections thus reuniting the adjustable tumbler sections for movement together as one. The new secondary key may then be removed for normal use with the primary key.

The invention thus provides a multiple key lock which can only be operated in normal use by employing the proper primary and secondary keys for which it is set up. The sections of the adjustable tumblers cannot be disconnected for adjusting the lock without first employing the correct secondary key of the series corresponding with the lock in order to remove the obstructing surfaces from the change key opening and then using a change key designed for the lock. When the change key is once inserted and the previous secondary key removed the change key is maintained in the lock and effectively holds its parts in

bolt releasing position with the bolt extended or in locked position. The change key can only be removed to again render the lock operative by the use of a proper secondary key which insures the setting up of the lock to such secondary key and not to a foreign instrument or to an ineffective position in the lock. These and other safeguarding advantages are obtained by a comparatively simple construction, requiring but a single set of tumblers and a single key barrel and bolt. By reason of this simplicity of construction the lock is inexpensive to manufacture and also more reliable and durable in operation.

I claim as my invention:

1. A lock comprising a bolt, adjustable key operated means for controlling the bolt, a device for adjusting said means to render the same responsive to different operating keys, and cooperating parts on said device and bolt for maintaining the latter in a given position during operation of said device.

2. A lock comprising a bolt, adjustable key operated means for controlling the bolt, a device for detachable insertion in the lock to adjust said means and render the same responsive to different operating keys, and cooperating parts on said device and bolt for maintaining the latter in extended position during complete operation of said device.

3. A lock comprising a bolt, adjustable means for controlling the bolt operated by keys inserted in one side of the lock, a change key for insertion in the other side of said lock to adjust said means and render the same responsive to selected ones of different operating keys and interengaging parts on said change key and bolt for maintaining the latter in extended position during complete operation of the change key.

4. A lock comprising a bolt having an opening therein, adjustable key operated means for controlling the bolt, and a change key for insertion in the lock through said bolt opening to render said means responsive to different operating keys and serving to maintain the bolt in extended position during such adjustment.

5. A lock comprising a bolt, changeable key operated means for controlling said bolt, a change key for insertion in the lock to change said means and render the same responsive to a selected one of a plurality of different operating keys, and cooperating parts on said bolt and change key for obstructing insertion of the latter except when said bolt is in extended position and for maintaining said bolt in extended position while said change key is inserted in the lock.

6. A lock comprising a bolt, changeable key operated tumblers for controlling said

- bolt, and a change key for insertion in the lock to change said tumblers to render the same responsive to selected operating keys, said tumblers and change key having a construction and arrangement obstructing insertion of the latter except when said tumblers are in bolt releasing position and serving to maintain said tumblers in said position while said change key is inserted in the lock.
- 10 7. A lock comprising a bolt, changeable key operated tumblers for controlling said bolt having openings therein, and a change key for insertion in the lock through said tumbler openings, when the tumblers are in bolt releasing position exclusively, to change said tumblers and render the same responsive to selected operating keys and serving to maintain the tumblers in bolt releasing position while inserted in the lock.
- 15 8. A lock comprising a bolt, changeable key operated tumblers for controlling said bolt, a change key for insertion in the lock to change said tumblers and render the same responsive to selected operating keys, a guard tumbler normally obstructing insertion of said change key and movable by any one of said operating keys to position for admitting said change key, and cooperating means on said guard tumbler and change key for obstructing withdrawal of the change key except while said guard tumbler is positioned by an operating key.
- 20 9. A lock comprising a bolt, changeable key operated tumblers for controlling said bolt, a change key for insertion in the lock to change said tumblers and render the same responsive to selected operating keys, a spring actuated guard tumbler normally obstructing insertion of said change key and having an opening therein, said guard tumbler being movable by any one of said operating keys to bring said opening to position for admitting the change key, and cooperating parts on said guard tumbler and change key for obstructing withdrawal of said change key except while said guard tumbler is positioned by an operating key.
- 25 10. A lock comprising a bolt, changeable tumbler means, a change key for insertion in the lock to render said tumbler means responsive to selected operating keys, guard tumbler means tending normally to obstruct insertion or removal of said change key, and movable by partial operation of any one of said operating keys to position for releasing said change key, and stop means limiting movement of said operating keys to said partial operation required for positioning the guard tumbler means.
- 30 11. A lock comprising a bolt, primary tumbler means controlling the bolt and responsive to a primary key, changeable secondary tumbler means controlling the bolt and responsive to secondary operating keys,
- a barrel receiving said secondary key and operated thereby, a change key for insertion in the lock to render said secondary tumbler means responsive to selected secondary operating keys, guard tumbler means tending normally to obstruct insertion or removal of said change key and movable by partial operation of any one of said secondary keys to position for releasing said change key, and cooperating parts on said barrel and bolt serving when said bolt is held extended by said primary tumbler means to limit the movement of the barrel and secondary key to said partial operation required for positioning the guard tumbler means.
- 35 12. A lock comprising a bolt, changeable key operated tumbler means controlling movement of the bolt, barrel means receiving the operating keys and actuated thereby to move the bolt, a change key for insertion in the lock to render said tumbler means responsive to selected operating keys, and also to maintain the bolt in a given position, guard tumbler means tending normally to obstruct insertion and removal of said change key and movable by partial operation of any one of said operating keys to position for releasing said change key, and cooperating parts on said barrel and bolt serving when the latter is maintained in said given position by the change key to limit the movement of the barrel and secondary key to said partial operation required for positioning the guard tumbler means.
- 40 13. A lock having a bolt, key operated means comprising a changeable tumbler device for controlling movement of said bolt, a change key for insertion in the lock when said means are moved to bolt releasing position by one operating key for changing said device to render the same responsive to a second operating key and for maintaining said means in said bolt releasing position, and cooperating parts on said means and change key obstructing withdrawal of the latter and released by insertion and actuation of said second operating key.
- 45 14. A lock comprising a bolt, adjustable tumbler means for controlling movement of the bolt and an adjusting device detachably insertible in the lock, when said tumbler means are moved to bolt releasing position by one operating key, for maintaining the tumbler means in said position and for adjusting said tumbler means to render the same responsive to a second operating key.
- 50 15. A lock comprising a bolt, adjustable tumbler means pivotally supported on a spindle for controlling movement of the bolt, and an adjusting device insertible in the lock at a point spaced laterally of said spindle when said tumbler means are moved to bolt releasing position by one operating key, for maintaining the tumbler means in said position.

sition and for adjusting the tumbler means to render the same responsive to a second operating key.

16. A lock comprising a casing provided with a keyhole, a bolt in the casing having a keyhole arranged for registry with said casing keyhole in extended position of the bolt, adjustable tumbler means controlling movement of the bolt, and an adjusting key insertible in said bolt and casing keyholes for adjusting the tumbler means to render the same responsive to a selected operating key and for maintaining the bolt in extended position during said adjustment.

17. A lock comprising a bolt, adjustable tumblers pivotally supported adjacent one end for key operation at the other to control movement of the bolt and having keyholes therein spaced from said supported ends and arranged to be brought into registry when said tumblers are moved by one operating key to bolt releasing position, and a change key insertible in said keyholes for adjusting said tumblers to correspond with a different operating key and for maintaining the tumblers in said releasing position during said adjustment.

18. A lock comprising a casing provided with a keyhole, a bolt in the casing having a keyhole arranged for registry with said casing keyhole in extended position of the bolt, adjustable tumblers in the casing pivotally supported adjacent one end for key operation at the other to control movement of the bolt and having keyholes therein spaced from said supported ends and arranged to be brought into registry with one another and with said bolt and casing keyholes when said tumblers are moved by one operating key to bolt releasing position, and a change key insertible in said keyholes for adjusting said tumblers to correspond with a different operating key and for maintaining said tumblers and bolt in said positions during said adjustment.

19. A lock comprising a bolt, adjustable tumblers pivotally supported adjacent one end for key operation at the other to control movement of the bolt and having keyholes therein spaced from said supported ends and arranged to be brought into registry when said tumblers are moved by one operating key to bolt releasing position, a guard tumbler having a keyhole therein and adapted to be moved to bring the latter into registry with the keyholes of said adjustable tumblers by any of the operating keys of the lock, a change key insertible into said registered keyholes for adjusting said adjustable tumblers to correspond with a different operating key and for maintaining said adjustable tumblers in bolt releasing position, and cooperating parts on said guard tumbler and change key for obstruct-

ing withdrawal of the latter during said adjustment.

20. In an adjustable lock, the combination of a bolt having a keyhole therein, adjustable tumblers provided with keyholes, a guard tumbler having a keyhole, said adjustable and guard tumblers being movable by one operating key to bring the keyholes thereof into registry with said bolt keyhole in a given position of the bolt, a change key for insertion in said keyholes to change said adjustable tumblers to correspond with a second operating key and to maintain said adjustable tumblers and bolt in position during said adjustment, and cooperating parts on said guard tumbler and change key for maintaining the latter in said keyholes during said adjustment.

21. In an adjustable lock, the combination of a bolt having a fence, adjustable tumblers each comprising a key operated sweep section and also a gated detent section having a keyhole arranged for registry with the keyholes of the other tumblers in fence releasing position, said tumblers being pivotally supported on a common axis with the sections of each tumbler movable relatively to each other transversely of said axis, interengaging parts on the sections of each tumbler for releasably connecting the same in different positions of relative adjustment and yieldable means tending to maintain said parts engaged, and an adjusting key insertible in said keyholes when the latter are brought into registry by one operating key to disengage said tumbler sections for positioning cooperation of the sweep sections with a second operating key.

22. In an adjustable lock, the combination of a bolt having a keyhole therein, adjustable tumblers each comprising a key operated sweep section and also a detent section having a keyhole arranged therein for registry with the keyholes of the bolt and the other tumblers in bolt releasing position, interengaging parts on the sections of each tumbler for releasably connecting the same in different positions of relative adjustment, means supporting the tumblers for movement by a selected operating key to bolt releasing position and also for movement of the sections of each tumbler relatively to each other to engage and disengage said parts, and an adjusting key insertible in the keyholes of the bolt and tumblers when brought into registry by one operating key to maintain said bolt and detent sections in position and to disconnect said tumbler sections for positioning cooperation of said sweep sections with a second operating key.

23. In an adjustable lock, the combination of a bolt, adjustable tumblers each comprising a key operated sweep section and also a detent section having a keyhole therein

arranged for registry with the keyholes of the other tumblers in bolt releasing position, interengaging parts on the sections of each tumbler for releasably connecting the same 5 in different positions of relative adjustment, a guard tumbler having a keyhole arranged for registry in bolt releasing position with the keyholes of the adjustable tumblers, means supporting the tumblers for movement by a selected operating key to bolt releasing position and also for movement of the sections of each adjustable tumbler relatively to each other to engage and disengage said parts, and an adjusting key insertible 10 in the keyholes of the tumblers when brought into registry by one operating key to maintain them in position and to disconnect said

tumbler sections for positioning cooperation of said sweep sections with a second operating key.

24. In an adjustable lock, the combination of a bolt, a single set of tumblers controlling the bolt certain of which are adjustable and which are provided with keyholes arranged to register with one another in bolt releasing 25 position, and an adjusting key insertible in said keyholes when the tumblers are moved to bolt releasing position by one operating key for maintaining the tumblers in said position and for adjusting the adjustable tumblers for cooperation with a second operating key.

WILLIAM F. DIESEL.
EUGENE R. WEBER.
